CLAIM

The ornamental design for an eye frame with gemstones on end tips, as shown and described.

DESCRIPTION

FIG. 1 is a top plan view of my new design;

FIG. 2 is a side elevational view of the outside thereof;

FIG. 3 is a side elevational view of the inside thereof; and,

FIG. 4 is a perspective view thereof.

The stippling and shading on the end tips represent gemstones. The broken lines are for reference only and form no part of the claimed design.

The end tip is shown separately in FIGS. 1-3 for ease of illustration only.
